UNITED STATES PATENT OFFICE

138,213

DESIGN FOR A BOOK COVER

Le Roy E. Hopkins, Northbrook, Ill., assignor to
Committee for Constitutional Government,
New York, N. Y., a corporation of the District
of Columbia

Application May 8, 1944, Serial No. 113,517

Term of patent 7 years

(Cl. D6—2)

To all whom it may concern:

Be it known that I, Le Roy E. Hopkins, a citizen of the United States, residing at Northbrook, in the county of Cook and State of Illinois, have invented a new, original, and ornamental Design for a Book Cover, of which the following is a specification, reference being had to the accompanying drawing, forming part thereof,

Figure 1 is a front elevational view of a book cover showing my new design.

Figure 2 is a side elevation on a reduced scale.

I claim:

The ornamental design for a book cover, as shown.

LE ROY E. HOPKINS.
